UNITED STATES PATENT OFFICE.

NELSON H. FOOKS, OF PRESTON, MARYLAND.

CAN-TRANSFERRING DEVICE.

1,402,488.

Specification of Letters Patent. Patented Jan. 3, 1922.

Application filed December 18, 1920. Serial No. 431,681.

To all whom it may concern:

Be it known that I, NELSON H. FOOKS, a citizen of the United States, residing at Preston, in the county of Caroline and State 5 of Maryland, have invented certain new and useful Improvements in Can-Transferring Devices; and I do hereby declare the following to be a full, clear, and exact description of the invention, such as will enable 10 others skilled in the art to which it appertains to make and use the same.

This invention relates to improvements in can transferring means adapted to be utilized in connection with an apparatus patented to me in United States Patent No. 15 1,354,962, dated October 7th, 1920.

It is an object of the invention to transfer cans or similar objects from a conveyer on one side of a partition to a conveyer on 20 the other side thereof without danger of obstructing the movements of the objects during the transfer.

In said prior patent there is disclosed a retort or fluid tight container divided into 25 two chambers by a transverse partition, said partition having an opening in its upper portion affording communication between said chambers. Each chamber contains a conveyer in the form of a revolving rack 30 having flights or ribs parallel with the axis of revolution, said ribs forming guideways between them, which cooperate with a spiral guide surrounding said racks concentrically in order to transfer cans through 35 each compartment serially in a spiral path, the spiral guide serving to move the cans continuously endwise between the ribs or flights.

In said prior apparatus the adjacent ends 40 of the concentric racks terminate close to the transverse partition, and a fixed cam or crossover, constituting a part of the spiral guide, shifts the cans endwise when they reach a position opposite the opening in said 45 partition. In said apparatus there is shown a gap between the ends of the flights of the separate racks across which it is necessary to push the cans. The usual cans for containing foods have a circumferential ridge 50 where the heads join the bodies and these ridges are likely to engage or drop into the space between the ends of the guideways on the racks or between the ends of the guideways on the racks and the partition. There 55 is also a possibility of the corners of the

flights being slightly distorted or misplaced and danger that a can may come in contact with said displaced portions and jam in the mechanism.

In the invention to which this application 60 relates, a smooth floor, composed preferably of a plate, curved substantially on the same arc as the peripheries of the racks, is interposed between the end of the racks and extends through the opening in the partition, 65 presenting a smooth surface on which the cans may be pushed endwise from one rack to another through said opening.

Furthermore, the receiving ends of the ribs or flights in a receiving chamber are 70 beveled, the bevels inclining from the outer edge of the ribs or flights to the inner edges thereof.

In the accompanying drawings:

Figure 1 is a section on the irregular line 75 1—1 of Figure 2, showing my improvement;

Figure 2 is a section substantially on the line 2—2 of Figure 1;

Figure 3 is a vertical longitudinal section 80 through the axis of an apparatus illustrating the position of the transfer floor;

Figure 4 is a section similar to Figure 3 illustrating the curved floor or transfer floor of modified construction; 85

Figure 5 is a diagram illustrating a fragment of the essential parts of my improvement developed in a plane;

Figure 6 is a diagrammatic perspective 90 of a fragment viewed diagonally from the left of Figure 1.

In the said drawings, 1 designates the cylindrical shell of a container such as a retort and P a partition dividing said retort into chambers H and C. Said partition P 95 has an opening at its upper edge providing for communication between said chambers over the curved edge P² of the partition. The said upper edge P² is curved on an arc concentric with the center of said shell 1. 100

Extending through said retort is a shaft 24 to which are secured spiders 27—27^a, the perimeters of which have substantially the same curvature as the upper edge P² of said partition P. Secured to the spiders 27—27^a 105 are angle bars, one flange 23—23^a of each angle bar extending radially parallel with the axis of shaft 24, and the other flange 23' or 23^a' extending at right angles to the radial flange. The flanges 23—23^a of said 110

angle bars serve as ribs or flights and receive between them cans or other objects to be treated, while the flanges 23'—23^a prevent the objects from falling through the 5 rack, and serve as supporting surfaces. The two racks arranged end to end on the common shaft 24 are thus provided with peripheral longitudinal guideways, the guideways of one conveyer extending in 10 alinement with those of the others.

Surrounding the said racks in each compartment and spaced from the ribs or flights is a spiral pathway formed by T-irons 21—21^a rigidly secured to the wall of the 15 retort and appropriately spaced from the said flights. Cans or other objects lying between the flights are forced to travel endwise along the racks when said racks rotate within said spiral guide, said racks and 20 spiral guide acting in the manner of a screw and nut to cause objects resting between the ribs or flights to travel in a spiral path through the said chambers.

The turns of the spiral guides 21—21^a 25 are so positioned with respect to the partition P that when a can has travelled through the chamber H to the partition it is in position to be shifted through the opening P' into the adjacent chamber C in order that 30 it may be moved spirally through the latter. In order to shift the cans from one rack to the other, it is necessary to move the cans endwise a distance equal to the space between two turns of the guides 21—21^a 35 within a distance equal to the circumferential extent of the opening in the partition. In order to cause the cans to move endwise as they reach the opening, a cam or crossover device S is fixed with respect 40 to said guides 21—21^a. This crossover may be, as shown, a channel iron secured to said spiral guide members and so constructed and arranged as to shunt the cans from the delivering end of one rack in one chamber 45 to the receiving end of the rack in the other chamber, the side flanges of said device S merging at each end, respectively, with the transverse flange of the guides 21—21^a.

50 In order to prevent the cans from being obstructed in the course of their passage across the partition P, a smooth, curved plate 80 is provided, on and over which, as on a floor, the cans are pushed endwise by the fixed cam or crossover device S. This plate is fixed in any suitable manner to the partition P and it is preferred that 55 said plate extend circumferentially in the form of a complete cylinder on each side of said partition so that the objects in the guideways cannot fall within the conveying racks. The said curved floor may be made of an integral plate of metal having alined kerfs 81 cut in from each end of a 60 width equal to the width of the partition 65

P leaving an undivided portion between the ends of said kerfs, said unbroken portion being of a length substantially equal to that of the curved portion of the edge P² of the partition. The said plate may be attached to the partition with the undivided portion fitted snugly upon the curved upper edge P² of said partition and the parts that are separated by the kerfs curved into cylindrical form until their ends meet. The 70 curved plate 80 may be secured to the partition by welding or otherwise. In the drawings I have indicated pieces of bar iron 82 formed into rings, said bar iron being riveted or otherwise secured to the partition P and serving as stiffening devices for the said curved plate 80 and means whereby it may be securely attached to said partition.

In order to provide room for the said 85 curved plate or flooring, the spiders 27, 27^a are spaced from the partition and the flanges 23', 23^a of the angle bars lying between the ribs 23, 23^a are cut away on each side of the central partition. The space 90 that would be otherwise occupied by said flanges 23', 23^a is filled by the said curved plate 80. It is preferred to construct and dispose said plate 80 so that the edge onto which a can is pushed in approaching the 95 opening of the partition is slightly nearer the axis of the racks than is the end of the flange 23' in juxtaposition therewith, in order that it may present no obstruction to the corner of a can as it moves endwise onto 100 said plate; and it is preferred that the delivery side of said plate 80 shall be correspondingly higher than the receiving end of the flange 23^a on the receiving rack. This may be accomplished either by depressing the receiving edge of the floor plate 80 and elevating its discharge edge, as illustrated, or by correspondingly elevating and 105 depressing the ends of the flanges 23' and 23^a of the discharging and receiving racks 110 respectively.

In order that objects may not fall or be pushed through or into the conveyer racks where the ends of the intermediate flanges 23' and 23^a have been removed, it is necessary that the floor 80 should extend circumferentially to points lower than the horizontal plane of the axis of the conveyer racks. Below that plane gravitational and centrifugal force tend to keep the objects 115 against the spiral guides 21, 21^a. But for the purpose of producing a strong construction and insuring that the objects cannot get inside the racks I prefer to form the member 80 as a cylinder.

Cutting away of the ends of the flanges 23', 23^a of the angle bars constituting the guideways for the cans on the rotary racks leaves the ribs 23 and 23^a unsupported at the ends adjacent the partition and sub- 120 125 130

ject to possible slight bending or distortion. If the ends of the receiving ribs or flanges were perpendicular to the axis of the racks cans might catch on said ends, 5 and so jam and interfere with the proper operation of the machine. In order to avoid danger of the can catching on the ends of the ribs on the receiving racks as the can is shifted endwise through the opening in the partition, the ends of said receiving ribs are beveled or inclined from the outer to the inner edges toward the partition as indicated at 83. As a result of 10 this construction, if there is any slight warping of the ribs or disalignment with respect to the delivering and receiving ends, the beveled ends 83 of the receiving ribs 23 will engage the shifting can and allow it to ride slightly upward on it, speedily 15 adjusting the can to the proper position between the ribs.

In the form shown in Figure 3 the plate or curved floor 80 is of a width adapted to allow the can to rest wholly upon said 25 plate as it is being shifted from one compartment to another. The said curved plate may be made much narrower, if desired, extending say an inch on each side of the partition P as indicated at 80^a in Figure 30 4. The relative positions of the discharge and receiving ends of the flanges 23', 23^a in this form of the invention should be the same as in the form in which the broad plate 80 is used. When the plate or transfer floor is narrow there is less likelihood 35 of displacement of the ends of the ribs 23, 23^a than when the plate is broad, because said ribs project or overhang a lesser distance in the former case. In the form 40 shown in Figure 4 a can completely bridges the space from the end of one flange 23' to the end of an alined flange 23^a and the strain of adjusting a moving can is received by a stiffer rib than in the other 45 form of the invention.

Having described my invention in such manner as to enable those skilled in the art to which it appertains to make and use the same what I claim and desire to secure by 50 Letters Patent of the United States is:

1. In mechanism of the class described, a partition, conveyers upon opposite sides of said partition adapted to move in unison parallel with said partition, said conveyers 55 having parallel ribs and supporting surfaces between them constituting object guideways, the ends of said ribs adjacent the partition projecting beyond said supporting surfaces, the guideways of one conveyer being in 60 alinement with corresponding guideways in the other, a floor member fixed with respect to the partition and extending over said partition beneath the projecting ends of said ribs so as to support objects moving from 65 one conveyer to the other, and means adapt-

ed to transfer an object from a guideway in one conveyer to a guideway in the other over said floor member.

2. In mechanism of the class described, a partition, rotary conveyers adapted to move 70 in unison on opposite sides of said partition, each conveyer having parallel ribs and supporting surfaces between them constituting object guideways, the guideways of one conveyer being in alinement with those of 75 the other, the ends of said ribs projecting beyond said supporting surfaces adjacent the partition, a curved floor member extending on opposite sides of said partition beneath the projecting ends of said ribs, and 80 means for engaging an object in the guideway of one conveyer and moving it endwise over said floor member from one conveyer to the other.

3. In mechanism of the class described, a 85 partition, rotary conveyers moving in unison on opposite sides of said partition in a direction parallel therewith, said conveyers having parallel ribs and supporting surfaces between them constituting object guideways, 90 the guideways of one conveyer being in alinement with the guideways of the other, the ends of said ribs adjacent said partition extending beyond said supporting surfaces, and a curved floor member projecting on 95 opposite sides of said partition beneath the ends of said ribs, said flooring extending around on each side of the axis of the conveyers to points below the horizontal plane of said axis.

4. In mechanism of the class described, a partition, rotary conveyers movable in unison on opposite sides of said partition in directions parallel therewith, said conveyers having parallel ribs and supporting surfaces between them constituting guideways, the guideways of one conveyer being in alinement with the guideways of the other, the ends of the ribs adjacent the partition extending beyond said surfaces, an approximately cylindrical member concentric with said conveyers fixed with respect to said partition and extending beneath the projecting ends of said ribs, and means for engaging an object and transferring it over said cylindrical member from one conveyer to the other across said partition on said cylindrical member.

5. In mechanism of the class described, a partition, conveyers on opposite sides of said partition adapted to move in unison in directions parallel therewith, said conveyers having ribs and intermediate supporting surfaces constituting guideways, the guideways of one conveyer being in alinement 125 with the guideways of the other, the ends of the ribs adjacent the partition projecting beyond said supporting surfaces, a floor member fixed with respect to said partition and extending on opposite sides thereof be- 130

- neath the ends of said ribs, means for trans-
ferring an object across the partition on
said flooring from one guideway to the
other, said floor having the edge adjacent
5 the intermediate surface of the delivery
guideways depressed below said surface, and
the edge adjacent the intermediate surface
of the receiving guideway elevated above
the latter.
- 10 6. In mechanism of the class described, a
partition, conveyers upon opposite sides of
said partition adapted to move in unison
and parallel with said partition, parallel
guide ribs on said conveyers, the ribs of one
15 conveyor being substantially in alinement
with the ribs of the other, means for trans-

ferring an object from one conveyer to the
other across said partition, the ends of the
ribs on the receiving conveyer being inclined
from their outer edges toward the partition. 20

7. In can conveying mechanism, two sepa-
rated but adjacent can supporting means
each having a guideway consisting of par-
allel ribs and an intermediate supporting
surface, the guideway of one supporting 25
means being in alinement with the guideway
of the other, the ribs of one guideway hav-
ing the ends adjacent to the other guideway
inclined from their outer edges toward the
adjacent guideway. 30

In testimony whereof I affix my signature.
NELSON H. FOOKS.
